UNITED STATES PATENT OFFICE

JAMES S. TAYLOR, OF TULSA, OKLAHOMA, ASSIGNOR OF ONE-HALF TO LORY J. MILDREN,
OF PONCA CITY, OKLAHOMA

CABLE CLAMP

Application filed January 14, 1930. Serial No. 420,757.

This invention relates to improvements in cable clamps.

The primary object of this invention is the provision of an improved clamp for support of drill cables and the like, having means associated therewith by which an enormous pressure may be brought to bear upon the cable clamping jaws of the clamp device; the improved cable clamp embodying 10 improvements on the cable clamp set forth in my United States Patent No. 1,675,996, patented July 3, 1928.

A further object of this invention is the provision of improved means for adjusting 15 the cable clamping liners of the jaws of a cable clamp, to compensate for wear thereon, or to adjust the improved clamp to particular sizes of cable being supported.

Other objects and advantages of this invention will be apparent during the course 20 of the following detailed description.

In the accompanying drawings, forming a part of this specification, and wherein similar reference characters designate corresponding parts throughout the several 25 views,

Figure 1 is a plan view, partly in section, showing the improved cable clamp with the jaws closed.

Figure 2 is a sectional view of the improved cable device, viewing the details 30 from the front, with the jaws closed.

Figure 3 is a fragmentary view of one of the jaws of the cable clamp, showing more 35 particularly the liner seat thereof.

Figure 4 is a view showing the relation of the cable clamping liners of the improved clamp device.

Figure 5 is a sectional view taken substantially on the line 5—5 of Figure 4.

Figure 6 is a side elevation, partly in section, of one of the cable clamp jaws.

Figure 7 is a front elevation of the outer ends of the cable clamp jaws, showing the 45 relation thereof.

Figure 8 is a front elevation of the means for bringing the jaws into clamping position.

Figure 9 is a sectional view of a modified 50 form of the improved cable device, viewing the details from the front with the jaws

closed; this modification having a reversible form of liner associated therewith and improved means to guide the cable into the grooves of the liner.

Figure 10 is a fragmentary plan view of 55 the modified form of clamp of Figure 9.

Figure 11 is a fragmentary view of one of the jaws of the modified form of cable clamp, showing more particularly the seat 60 for the liner and an adjacent groove used for receiving the sand line therein.

Figure 12 is a perspective view of the improved modified form of liner.

Figure 13 is a sectional view taken substantially on the line 13—13 of Figure 10. 65

Figure 14 is an enlarged sectional view taken across the liner of Figure 12, substantially on the line 14—14 in Figure 12.

In the drawings, wherein for the purpose of illustration are shown preferred and 70 modified embodiments of the invention, the letter A may generally designate the improved clamp, which may include a supporting body B, having clamp jaws C and D pivotally mounted thereon for the gripping of a cable therebetween. Means F is provided for relatively adjusting the jaws C and D in the body B. 75

The body B, as well as other parts of 80 the invention, may be made of durable metal construction, of a nature best adapted to support the heavy weight of a cable and drill tools supported thereby. It includes the substantially concavo-convex frame 10,

having one face 11 thereof concaved, and 85 the opposite side convex. At the opposite side edges the said portion 10 is provided with forwardly extending flanges 12 and 13, throughout the height of the portion 10, to define a channel therebetween and of which

the concave surface 11 forms the bottom, as 90 is shown in Figure 1. At the upper and lower edges thereof the frame 10 is provided with the transversely extending reinforcing flanges 14 and 15, as more particularly

shown in Figure 2 of the drawings. The flanges 12 and 13 are convexly bowed inwardly into the channel space therebetween, at 95 16 and 17, preferably throughout the height thereof; the ends of the flanges 12 and 13, 100

in fact, forming barrel portions provided with passageways 18 therethrough, adapted to receive pivot pins 19 and 20 respectively, for respectively pivoting the jaws C and D thereto, as will be subsequently mentioned. 5 The upper and lower surfaces of the body B are preferably flat and parallel.

The jaw constructions C and D are formed in lefts and rights respectively, and 10 have their respective bearings on the flanges 12 and 13, more particularly at the convex surfaces 16 and 17. They are of the same general construction, except at the forward ends thereof, and each includes a main body 15 portion 35, provided with one side thereof concaved at 36, longitudinally thereof from top to bottom, for receiving therein the convexities 16 and 17 of the body B, as shown in Figure 1 of the drawings. The radii 20 from which the convex surfaces 16 and 17 and the concave surfaces 36 are struck, are all equal, so that the jaws C and D have an accurate bearing on the convex barrel portions of the body B, which extend into 25 the channel between the extensions 12 and 13. The jaws C and D each have upper and lower lateral extensions 37 and 38 respectively, adapted to overlie rather snugly the upper and lower surfaces of the body B, 30 as shown in Figure 2; said extensions 37 and 38 being apertured at 40° for alignment with the apertures 18 of the barrel portions of the body B, to receive the pivot pins 19 and 20 for pivoting the jaws C and D respectively to the body B. The pintles or pins 19 and 20 may have heads integral at the lower ends thereof and detachable cotter pins 41 at the upper ends thereof to facilitate connection, if desired, as shown in Figure 2. 35

40 Notwithstanding the provision of the pintle pins 19 and 20, the wear does not take place directly thereon, incident to a clamping action, but is placed directly upon the convex surfaces 16 and 17 upon 45 which the said jaws C and D pivot.

Each of the jaw bodies 35 is provided forwardly thereof with the forwardly extending and relatively converging upper and lower arms 40 and 41, more particularly 50 shown in Figure 6 of the drawings, which are connected at their free ends in forwardly extending shanks 42^a and 43^a for the jaws C and D respectively, with which the means F cooperates to draw the jaws together into 55 a cable clamping position.

The jaws C and D at the facing sides thereof are each longitudinally recessed, at 42 and 43 respectively; said recesses 42 and 43 being polygonal shaped in cross section, 60 providing opposite parallel faces and a bottom; the bottom of each of said recesses tapering downwardly with respect to the normal clamping axis of the cable, so that the bottoms of the recesses 42 and 43 are 65 relatively convergent downwardly, as shown

in Figure 2 of the drawings, which is for the purpose of enabling the liners 45, which seat in said jaws C and D, to be adjusted for wear compensating purposes, and to suit them to particular sizes of cable. The flanges at the facing sides of the body 35 of each of the jaws C and D are particularly 70 cut down to the bottom of the recesses 42 and 43, intermediate the ends of the body 35, as more particularly shown at 46 in Figure 2 of the drawings, and in this location the bottoms of the recesses 42 and 43 are provided with sockets 47, or supporting teeth or serrations, defining upwardly facing preferably horizontal surfaces with 75 which retaining lugs 48 at the outer sides of the liners 45 may cooperate in selective relation.

The liners 45 are illustrated in Figures 4 and 5 of the drawings, and the same are 80 formed so that they may be used in either the jaw C or D, without the necessity of making the same rights and lefts. In cross section they are polygonal, having opposite parallel sides 50 and 51, with a sloping surface 52 adapted to engage against the bottom of the recess in the jaw in which seated. The face of each of the liners is provided with a longitudinal concavity 54 adapted to receive the cable therein. With respect to 85 the axis of the concavity 54, the sloping surface 52 opposed thereto converges downwardly. Thus, the liner 45 is tapered with respect to the concavity 54 downwardly in a convergent relation; the liner being widest at its upper end and gradually decreasing towards the lower end thereof. The surfaces 52, are adapted to seat against the sloping bottoms of the recesses 42 and 43 of the respective jaws in which placed, and the polygonal cross section of the recesses and the liners prevents relative rotary movement of the same. When in position, as shown in Figure 1, the liners snugly seat in their jaw recesses with the concavities 54 90 facing to clamp a cable therein. The lugs 48 are provided in outstanding relation from the surfaces 52, about midway between the upper and lower ends of the liner; said lugs 48 forming detents with preferably 95 lower horizontal surfaces. The detents 48 are adapted to selectively seat in or upon the sockets or teeth 47, for longitudinal adjustment of the liners in the jaws C and D, for wear compensating and other adjusting 100 purposes.

In order to hold the liners in the position in which adjusted, the said liners are provided in opposed sides thereof with slots 56, preferably above the lugs 48, and into which 105 the pointed ends of set screws 57 may adjust; the set screws 57 being adjustably threaded in screw threaded openings 59 provided in the flanges of the jaw bodies 35, as shown in Figures 1 and 2 of the draw- 110

ings. These screws 57 are placed at an acute angle with respect to a plane normal to a line intersecting the pivot axes of the jaws, in order that the clamping effect of the set screws will have a tendency to seat the liners 45 more firmly in their recesses or sockets in the jaws. When the jaws are in cable clamping position the screws 57 are convergent in the direction of the heads thereof. The heads of the screws of course may be easily reached for adjustment, inasmuch as they are at the fronts of the bodies 35 about midway between the arm portions 40 and 41 of the jaws; the boss 60 in Figure 6 representing the location of the screw threaded sockets provided for receiving a set screw 57.

It is preferably a feature of this invention, as it is also a feature of the invention of my above mentioned patent, that when the jaws C and D are clamped upon a cable to support the same, the center of the cable as supported by the liners of the jaws will lie forwardly a fraction of an inch from a line drawn straight between the pivot axes of the jaws C and D. The arrangement insures a substantially right angled purchase of the lever jaws on the cable, in order that a powerful clamping action may take place.

Means is provided to insure a uniform opening and closing of the jaws C and D, in order to produce an efficient clamping action on a cable. This is provided by placing on the rear of the bodies 35 of the jaws C and D, fingers 65 and 66 respectively, facing in the channel of the body B, and operating respectively at their convex edges 67 upon the convex surfaces 68 of the adjacent jaws, as shown in Figure 1 of the drawings. This is a feature of my patent above referred to, and it is apparent from the description herein, and in my patent that inner and outer movement of the jaws will be effected in the same degree, due to the riding of the surfaces 67 on the surfaces 68.

The means F for clamping the jaws C and D together preferably comprises a link-shaped member 70, shown in Figure 8 of the drawings, consisting of upper and lower parallel bars 71 and 72 connected at similar ends of each by a cross bar or bight portion 73, presenting a concave surface 74 to the space between the bars 71 and 72. At its opposite end the link 70 has the bars 71 and 72 connected by a cylindrical portion 75, having a screw threaded passageway 76 therethrough. The passageway 76 receives an adjusting bolt 77 of T-shaped formation, having a screw threaded shank 79 and a handle 80 thereon in right angled relation to the axis of the shank 79. The shank 79 adjusts into the space between the bars 71 and 72, and is provided with a jaw clamping abutment 82 thereon.

The jaw C at its free end is provided with

the reduced connecting shank 42^a having at the outer side thereof a concave socket 84 facing away from the other jaw D. It is adapted to receive therein the bight 73 of the clevis or yoke body 70, in such relation that the latter may be swung to position the free ends of the jaws C and D in the space between the bars 71 and 72.

The reduced end 43^a of the jaw D, is provided at the outer end thereof with upper and lower detachable retaining extensions 87 and 88, screw threaded at 89 thereon, defining grooves in the upper and lower surfaces of the jaw D, at its free end, between the arms 40 and 41, and their respective upper and lower retaining pieces 87 and 88. In these grooves lie the bars 71 and 72 of the clevis member 70; the distance between the upper and lower extreme surfaces of the retaining blocks 87 and 88 being greater than the height of the opening in the clevis member 70, so that the said member may be swivelly connected to the jaw D in a freely movable relation, and in position so that its free end may be moved to engage the socket 84 of the jaw C. Of course, the screw 77 is longitudinally adjustable into the elongated opening 90 of the clevis member 70, and adapted to engage in a socket 91 provided therefor at the outer side of the lug 43 of the jaw D. It is relatively understandable that upon threading the screw 77 into the opening of the clevis member 70, the jaws C and D will be brought together for clamping the liners against a cable for supporting purposes.

As an improved feature of the invention it is preferred to provide hooks 96 and 97 at the tops of the jaws C and D respectively, integral with the bodies 35 thereof, and extending laterally from the arms of said jaws; said hooks 96 and 97 being of inverted J-shaped formation and with their free ends spaced above the top surface of the body B, to facilitate the slipping of conventional reins therein for supporting the clamp from the temper screws of conventional well drilling apparatus. This feature of providing the hooks on the pivoted jaws is in contradistinction to the structure set forth in my patent above referred to, and is best under practical conditions.

Referring to the modified form of invention illustrated in Figures 9 to 14 inclusive, the same utilizes a body B of exactly the same construction as the body B above described, and similar reference characters have been applied to said body B for all forms of the invention. In the modified form of invention jaws C' and D' are provided, which in like manner with the preferred form of invention are in lefts and rights respectively, and are supported and related to the body B in the same manner as above described for the preferred form of

invention. Insofar as applicable, similar reference characters designate corresponding parts of the jaws in both forms of invention.

5 So far as modification of the jaws C' and D' are concerned, at the facing sides thereof they are respectively provided with longitudinal recesses 42^a and 43^a respectively, which are shaped similar to the recesses 10 42 and 43 of the jaws C and D of the preferred form of invention, as can readily be seen from the drawings. An improved type of liner 100 is utilized in connection with each of the jaws C' and D', which is adaptable to be used in either jaw, or reverse in either jaw. The liner 100, as shown in Figure 12, has opposite faces 101 and 102 in parallelism, and along opposite sides, which are normal to the surfaces 101 and 102, the 15 liner 100 is provided with longitudinal cable receiving grooves or sockets 103 and 104, which may be of the same cross section or different cross section, as desired. The sides in which the grooves 103 and 104 are formed 20 taper convergently from the upper end of the liner downwardly to the lower end 106 thereof, as is shown in Figure 12 of the drawings. The sockets 42^a and 43^a for the liners 100 are of such size that the liners 25 seat therein so as not to permit any appreciable projection of the facing sides of the liners beyond the facing sides of the jaws, and in this position the facing grooves of the liners of the jaws C' and D' are complementary for receiving a cable, as can be seen in Figure 10 of the drawings. It is readily appreciable that the liners 100 are 30 reversible in each of the jaws, and may be placed in either jaw. The advantages of 35 such arrangement are well apparent.

40 In order to hold the liners in the position in which they are placed, against relative movement transverse to or longitudinally of the respective jaw opening position, 45 the said liners are each provided, on each side 101 and 102 thereof, with two longitudinal series of circular or other shaped sockets. Thus, as shown in Figure 12 a series 107 of such sockets are arranged longitudinally of the liner, on the surface 101, closer to the 50 groove 103 than the other groove 104, and similarly a second series of such sockets 108 are provided, in a line parallel with the adjacent edge of the liner, but closer to the 55 groove 104 than the groove 103. As is shown in Figure 14 these series of sockets are provided on each of the faces 101 and 102 of each liner, to permit the reversibility of the liners as above mentioned. Set 60 screws 110 are adjustably threaded into suitable screw threaded openings 111 provided in the flanges of the jaw bodies 35 of the jaws C' and D', as shown in Figures 9 and 65 10 of the drawings, in much the same manner as the positioning of the set screws 57

for the preferred form of invention above described. The set screws are positioned acute to the plane of the liners, to more effectively seat the latter, and the ends of the screws 110 engage in the sockets 107 or 70 108, depending upon the positioning of the liners 100, as is quite apparent from Figure 10 of the drawings.

75 The jaws C' and D' are modified over the jaws C and D of the preferred form of invention, in the provision of reduced guide extensions 113 and 114, at the tops of the jaws C' and D' respectively. At the handle sides of the liner grooves or recesses 42^a and 43^a respectively, to serve as guides for directing the rope or cable into the grooves of the liners, as will be well apparent to those skilled in this art. In addition, these extensions 113 and 114, which are positioned 80 at the handle side of the respective liner recesses, are also provided at the upper ends thereof above the recesses 42^a and 43^a with transversely extending bosses 115, more particularly shown in full lines in Figure 11, and in dotted lines in Figure 9, as a further 85 aid in directing the rope into the liner grooves.

90 As a further feature of the modified jaw construction, grooves 116 and 117 are provided in the facing sides of the jaws C' and D' respectively, in parallelism with the liner sockets 42^a and 43^a, but between the handles of the respective jaws and said liner recesses; the said grooves 116 and 117 extending upwardly along the extensions 113 100 and 114, as is shown in Figure 11 of the drawings. These grooves are adapted to receive the sand line, and are cut in front of the liner seats, and run parallel therewith to enable an expeditious holding of the sand line while splicing or fishing, or for any other purpose when it is required to clamp the sand line when the latter is to be run into the well opening, but cannot be used 105 while the cable is clamped.

110 Various changes in the shape, size, and arrangement of parts may be made to the forms of invention shown and described, without departing from the spirit of the invention or the scope of the claims.

115 I claim:

120 1. In a cable clamp a supporting body, jaws movably connected upon the body, means to move the jaws towards and away from each other for clamping a cable therebetween, said jaws having polygonal shaped recesses therein, liners in said sockets of polygonal form fitting snugly into said sockets in a non-rotatable relation, said liners having facing sockets for the clamping 125 of a cable therein between the liners, and means for adjusting the liners relatively towards and away from each other independent of corresponding movement of said jaws.

2. In a cable clamp a pair of jaws, means movably supporting the jaws, the facing surfaces of the jaws having a series of spaced sockets therealong in a line transverse to the plane of movement of the jaws, and liners for each of the jaws having means cooperating therewith to selectively fit in the sockets for adjusting the liners in a predetermined relation.
- 10 3. In a cable clamp a body, a pair of jaws pivoted on the body, the jaws in facing relation having recesses the bottoms of which are relatively convergent in a line transverse to the plane of movement of the jaws, the bottoms of said recesses having series of sockets therealong, and liners having surfaces in abutment with the converging surfaces in the recesses of said jaws, the liners having extensions thereon adapted for selected fitting in the series of sockets of their respective jaw recesses for adjustment of the liners in a predetermined relation along their respective jaw recesses.
- 25 4. In a cable clamp a body, a pair of jaws pivoted on the body, the jaws in facing relation having recesses the bottoms of which are relatively convergent in a line transverse to the plane of movement of the jaws, the bottoms of said recesses having a series of sockets therealong, liners having surfaces in abutment with the converging surfaces in the recesses of said jaws, the liners having extensions thereon adapted for selected fitting in the series of sockets of their respective jaw recesses for adjustment of the liners in a predetermined relation along their respective jaw recesses, and set screw means for holding the liners in a predetermined clamped relation in their recesses.
- 30 5. In a cable clamp the combination of a body comprising a substantially channel-shaped frame having opposed side flanges in facing relation, the flanges being provided with facing convex surfaces in the channel groove which are continuous from the top to the bottom of the channel, parallel with the channel way, jaws having concave grooves therealong for receiving said convex surfaces of the channel flanges, and means
- 35 pivotally connecting the jaws on said body in such relation.
- 40 6. In a cable clamp the combination of a supporting frame including a channel-shaped body provided with opposed side flanges having facing convex surfaces therealong, a pair of jaws having concave grooves for snugly fitting in said convexities of the flanges, the flanges of said frame having passageways therethrough, the jaws extending
- 45 beyond the ends of the channel-shaped frame and having apertured lugs fitting over the frame, with the apertures thereof aligning with the adjacent passageways of said channel flanges, and pintles pivotally connecting said jaws, extending into the apertures
- 50 of the lugs and passageways of the channel flanges.
- 55 7. In a cable clamp the combination of a supporting body, a pair of jaws pivoted on the supporting body, the jaws in the facing surfaces thereof having facing recesses of polygonal cross section and with the bottoms thereof tapering in converging relation in line transverse to the plane of movement of the jaws, liners adjustably fitting in the recesses against said converging surfaces, means to hold the liners in position, said last mentioned means including positive interlocking means between the liners and jaws to prevent sliding of the liners along the jaws, and set screw means holding said interlocking means in a desired connected relation.
- 60 8. In a cable clamp the combination of a body, jaws movable upon the body, liners adjustable on the jaws, the liners having grooves longitudinally thereof, and a set screw on each jaw for each liner adjustable into the grooves of the liner into a locked engagement with the liner.
- 65 9. As an article of manufacture a reversible liner for the jaws of cable clamps comprising an elongated longitudinally tapered body having longitudinally converging cable clamping recesses in opposite edges thereof, the opposite sides of said liner being normal to the edges in which said cable receiving recesses are disposed, and said opposite sides each having a pair of spaced longitudinal series of clamping sockets arranged therealong.
